CLAIM

The ornamental design for a tabletop point-of-sale (POS) terminal, as shown and described.

DESCRIPTION

FIG. 1 is a front perspective view of the tabletop point-of-sale (POS) terminal according to the new design.

FIG. 2 is a front elevation view of the tabletop point-of-sale (POS) terminal.

FIG. 3 is a rear elevation view of the tabletop point-of-sale (POS) terminal.

FIG. 4 is a right side view of the tabletop point-of-sale (POS) terminal.

FIG. 5 is a left side view of the tabletop point-of-sale (POS) terminal.

FIG. 6 is a top view of the tabletop point-of-sale (POS) terminal; and,

FIG. 7 is a bottom view of the tabletop point-of-sale (POS) terminal.

The broken lines in the drawings depict portions of the tabletop point-of-sale (POS) terminal that form no part of the claimed design.

The article in which the design is embodied is a user terminal for conducting tabletop point-of-sale (POS) terminal in a retail environment.
